M. J. KELLY

VACUUM TUBE MANUFACTURE

Filed June 30, 1921

Inventor:
Mervin J. Kelly

by W. Beatty Atty

UNITED STATES PATENT OFFICE.

MERVIN J. KELLY, OF NEW YORK, N. Y., ASSIGNOR TO WESTERN ELECTRIC COMPANY,
INCORPORATED, OF NEW YORK, N. Y., A CORPORATION OF NEW YORK.

VACUUM-TUBE MANUFACTURE.

Application filed June 30, 1921. Serial No. 481,610.

To all whom it may concern:

- Be it known that I, MERVIN J. KELLY, a citizen of the United States of America, residing at New York, in the county of New York, State of New York, have invented certain new and useful Improvements in Vacuum-Tube Manufacture, of which the following is a full, clear, concise, and exact description.
- 10 This invention relates to induction furnaces and more especially to their use in the manufacture of vacuum tubes for denuding the electrodes of occluded gases during the exhaust of the tubes.
- 15 An object of this invention is to heat the vacuum tube electrodes by supplying electrical energy to them inductively.

According to the invention high frequency oscillations are supplied to an induction coil within which is arranged a vacuum tube having electrodes to be heated. The oscillations supplied to the coil generate an electromagnetic field within the coil which induces eddy currents in the electrodes to heat them. As the eddy currents produced are proportional to a power of the frequency greater than the first, it is desirable that the frequency be of a very high order. Preferably an audion oscillator is used as a source of oscillation as frequencies of the order of 500,000 cycles may be readily obtained from such a source. When used in connection with vacuum tubes having cylindrical anodes, such a device is extremely effective in heating the electrodes as it is possible to obtain a very close coupling between the coil and the electrode by arranging the electrodes coaxial of the coil.

This invention will be better understood by having reference to the following specification and accompanying drawing wherein is disclosed somewhat diagrammatically an apparatus for producing the electromagnetic field and is illustrative of the method of heating the anode thereby.

The vacuum tubes 1 to be exhausted are connected to a vacuum pump (not shown) by means of the glass tubing 2. Arranged within the vacuum tubes are the anodes 3 which are to be denuded of their occluded gases. The anodes are heated to the desired temperature by means of an induction furnace which comprises the coils I and I'. These coils together with the variable condensers 11 and 12 comprise an oscillation

circuit. The frequency of oscillations generated in this circuit is dependent upon the sum of the capacity reactance of the condensers 11 and 12 and upon the inductive reactance of the coils I and I'. 60

As a means for supplying exciting current to the oscillation circuit, there is provided an electron discharge oscillator which comprises a vacuum tube V having the cathode F, the control electrode C and the anode A, the input and output circuits of the tube being connected with the oscillation circuit between the coils I and I' and the variable condensers 11 and 12 respectively. Included in the output circuit of the oscillator is a generator G and a high frequency choke coil 13. In the input circuit of the oscillator is provided a small resistance 14 to prevent high frequency singing in said circuit, and a grid leak resistance 15 in combination with a condenser 16 maintains the average grid potential. The connections of the input and output circuits of the oscillator to the oscillation circuit comprises stopping condensers 17 to prevent direct current flowing into the oscillation circuit. The cathode of the vacuum tube V is grounded at 18 to protect both the input and output circuits of the oscillator against any accidental grounding of either of the circuits. Heating current is supplied to the cathode F by the battery 19.

This arrangement is capable of generating, in the oscillation circuit, oscillations of the order of five hundred thousand cycles 90 which has been found to be the frequency at which the desired eddy currents are obtainable with the minimum expenditure of energy from the generator G. These oscillations produce the high frequency field 95 which induces in the anode of the tube to be exhausted the eddy currents by means of which the anodes are heated.

In order to provide a close coupling between the anodes 3 of the tubes to be exhausted and the coils I and I' the tubes are inserted in the coils and the anodes are made cylindrical and arranged comparatively close to the inner wall of the tube, the coils I and I' being of the proper diameter to 100 snugly receive the tubes. The anodes are thus coaxial with the coils and the tubular configuration thereof provides a circumferentially complete path for the eddy currents induced by the coils, these currents 110

- being at right angles to the axes of the coils. The coils are preferably approximately of the same length as the anodes 3 and are of the standard multi-layer type.
5. During the exhaustion of the tubes the high frequency current is supplied to the coils I and I' thereby producing an electromagnetic field parallel to the axes of the anodes. There are, therefore, induced in
- 10 the anodes Foucault currents which, because of the tubular configuration of the anodes, have circumferentially complete paths and which generate in the anode sufficient heat to drive out therefrom any
- 15 occluded gas. Because of the extremely high frequency of the current supplied to the induction coils and because of the close coupling between the coils and the anodes due to the configuration of the anodes and
- 20 their position in the coils this arrangement is highly efficient and the necessary temperature can be obtained by the expenditure of a comparatively small amount of electrical energy.
- 25 The temperature to which the electrodes are heated can be controlled by varying the high frequency current in the oscillation circuit. This can be done by varying the alternating potentials across the input and
- 30 output circuits by varying the capacities 11 and 12; or it may be done by varying the potential of the generator G.
- Although this apparatus is disclosed as being adapted for heating the anodes of
- 35 vacuum tubes, it may be used for heating any metal.
- What is claimed is:
1. A method of exhausting a vacuum tube having an anode by the use of a thermionic oscillator having an inductive element which
- 40 comprises surrounding said vacuum tube by said inductive element and producing a high frequency electromagnetic field in said inductive element to directly heat the anode
- 45 of said vacuum tube.
2. A method of exhausting a vacuum tube having a cylindrical anode by the use of a
- high frequency thermionic oscillator having an inductive element serving as an induction heater, which comprises producing a high frequency alternating current by said oscillator in said inductive element, and heating the anode of said tube by subjecting it to the electromagnetic field produced in said inductive element with the axis of the anode parallel to the lines of force of the field.
3. In combination, a thermionic oscillator comprising an induction coil for producing an electromagnetic field, and a vacuum tube having an anode arranged within said coil whereby the electromagnetic field is effective to produce eddy currents in said anode.
4. In combination, a source of electrical energy, a vacuum tube having its output circuit connected with its input circuit whereby a portion of the energy of the output circuit is fed back into said input circuit, an induction coil having its terminals connected with the control electrode and anode of said vacuum tube, and a vacuum tube having an anode arranged within said coil whereby current supplied to said induction coil is effective to produce eddy currents in said anode.
5. Apparatus for exhausting a vacuum tube having a cylindrical anode comprising a thermionic oscillator for supplying high frequency alternating current, and an inductive coil forming a part of said oscillator and arranged to receive said tube with the axes of the anode and the coil coincident.
6. An oscillator having capacity reactance and inductance reactance for determining the frequency generated, said inductive reactance comprising a coil, a vacuum tube within said coil having an electrode adapted to be heated by the eddy currents produced by the field due to said coil and a pumping passage communicating with said vacuum tube for removing the gases denuded from said electrode by said heating.
- In witness whereof, I hereunto subscribe my name this 28th day of June, A. D. 1921.
- MERVIN J. KELLY.
